UNITED STATES PATENT OFFICE.

ROBERT REX DOWNIE, OF BEAVER FALLS, PENNSYLVANIA, ASSIGNOR TO KEYSTONE DRILLER COMPANY, OF BEAVER FALLS, PENNSYLVANIA, A CORPORATION OF PENNSYLVANIA.

EXCAVATING MACHINE.

Application filed January 28, 1925. Serial No. 5,249.

To all whom it may concern:

Be it known that I, ROBERT REX DOWNIE, a citizen of the United States, residing at Beaver Falls, in the county of Beaver and State of Pennsylvania, have invented a new and useful Excavating Machine, of which the following is a specification.

This invention relates to excavating machines, and particularly to those of the drag stick, ditcher type, such as that disclosed in United States Patent No. 1,511,114, granted to me October 7, 1924, and it consists primarily in an improved device for controlling the position of the ditcher scoop.

15 The object of the present invention is to provide an improved construction which will permit a much greater latitude in the positioning or spotting of the loaded scoop when elevated as for dumping, and will permit greater positiveness and accuracy in controlling the position of the scoop within that range than is otherwise feasible.

To the attainment of the foregoing, the invention comprises a modification in the 25 form of the upper end of the ditcher stick, and of the means connecting the same to the hoisting line, so as to effect a shifting of the point at which the hoisting line stress is delivered to the upper end of the stick, 30 whenever there is a change in the inclination of the boom, or in the angle between the boom and the stick. In the specific embodiment of the invention, which is herein described and illustrated, this connecting 35 means comprises a flexible member in lieu of the stiff connecting bar previously used, and the upper end of the stick is extended in the plane of its up and down movement to form an upwardly bowed head having 40 a groove in its upper face for receiving and guiding said flexible member, and adapted to maintain, at all times, a sufficient distance between the line in which the hoisting force is applied and the pivotal connection 45 of the stick with the boom.

The specific construction of the invention, as well as its advantages and its mode of operation, will be more fully explained in the detailed description which follows, 50 which is to be read in connection with the accompanying drawings, illustrating one embodiment of the invention.

In the drawings:

Figure 1 is a side elevation of the invention showing the boom raised.

Figure 2 is a similar view showing the boom lowered, and the scoop at its outermost position, as at the beginning of an excavating operation.

Figure 3 is a similar view showing the 60 position of the ditcher stick and scoop after they have been drawn in.

The invention is shown in connection with an excavating machine 1, having a mast 2, which is connected thereto by a pair of vertically aligned pivots 3. A boom 4 is pivotally connected, as at 5, to the lower end of the mast, and is adapted to be moved upwardly and downwardly about its pivot 5, and the boom may be swung laterally with the mast 70 65 about the pivots 3. The outer end of the boom has extension irons 6 secured thereto, the outer ends of which are traversed by a pivot bolt 7 for supporting a ditcher stick 8. A scoop 9 is secured in the usual manner to the lower end of the ditcher stick, and has a hauling bail 10 pivoted thereto to which is attached a hauling cable 11.

A bearing block 12 is secured to the inner side of the ditcher stick near its upper end 80 for receiving the pivot bolt 7, and on the outer side of the ditcher stick somewhat above the block 12 is secured a bearing block 13, which receives a pivot bolt 14 to which is connected the means for applying force for hoisting the boom and scoop, 85 and for spotting the latter. In the present construction, this means comprises a flexible element, composed of a series of links as indicated at 15, which is connected at its 90 outer end to the pivot bolt 14, and is connected at its inner end to a pivot bolt 16, the latter having a sheave 17 journaled thereon about which passes the hoisting cable 18. When the boom is lowered, and the ditcher stick and scoop extended, as shown in Figure 2, the flexible element 15 is straight and in alinement with the hoisting line of tension. The upper end of the ditcher stick 8, however, is provided with an upwardly bowed extension or head 19 95 disposed in the plane of movement of the ditcher stick as it moves about the pivot 7, and having in its upper face a groove 20 for engaging and guiding the flexible member 15 as the boom is raised and lowered, or the scoop and ditcher stick moved about the pivot 7. Thus, the extension or head 19 engages and flexes the connecting member 15 to effect a gradual shifting of the 100 105 110

point at which the hoisting line stress is delivered during the operation of the machine.

It will be understood that the operation 5 of raising and lowering the boom 4 and the ditcher stick 8 carried thereby, and of moving the ditcher stick and the scoop 9 outwardly and inwardly about the pivot 7 for filling the scoop and for positioning preparatory to dumping the same is controlled entirely through the cables 11 and 18, as explained in the above mentioned patent. In said patent, however, the sheave 17 was connected to the pivot bolt 14 by a stiff connecting bar, and with such a construction when the pivot bolts 7 and 14 are properly located with respect to the line of tension in the hoisting line to give the best results with the greatest conservation of power, under certain conditions the pivot bolt 7 will be substantially in the line of pull between the cable 18 and the pivot 14, so that it is difficult to swing the scoop outwardly to gain the desired spotting range. It is in order to prevent this condition without altering the relative locations of the pivot bolts 7 and 14 that I have devised the present construction, whereby, when the pivot bolt 14 is in what might be termed dead center position, the flexible member 15 is engaged by the head 19 and swung upwardly, so as to shift the point of application of the hoisting force, and increase its effective leverage, thus providing means for positively and effectively swinging the scoop outwardly by paying out the cable 11 and drawing in on the cable 18, regardless of the elevation of the boom.

The effect of the construction herein described is to give the desired degree of positiveness of action in bringing the scoop to the exact position desired for dumping. The spotting range is increased to about twice the range possible without this improvement, and without any offsetting disadvantages.

It is not feasible to attain this increased spotting range by altering the relative location of the pivots 7 and 14. Such alteration would result in a prohibitive waste of power, or would sacrifice to a prohibitive degree the outward reach of the stick when lowered and extended at the beginning of the operation. The position of the pivots 7 and 14 is actually governed by considerations of power economy and necessary digging travel or sweep of the scoop, and can not, therefore, be altered in order to gain the desired spotting range or outward dumping reach.

In excavators of this type, for example, the pivot 14 is located a certain distance above the pivot 7. The purpose of this relative arrangement is to cause the tension of the hoisting line 18 not only to support the

stick and attached parts, but also to maintain a pull upon the upper end of the stick in the direction of the machine, and, with the boom acting as a stiff link, to cause the stick to swing outwardly nearly into longitudinal alinement with the boom. It is obvious that this initial reach is desired, and is, in fact, indispensable in starting the excavation down through a level surface. The stick assumes and remains in this position of rest or equilibrium, except as restrained or retracted from it by the hauling line 11, which is attached to the bail 10 on the scoop. Digging is effected by first lowering the boom, stick and scoop in this extended position until the teeth of the scoop engage the material to be excavated, and then winding in the hauling line.

It will be seen that the hauling line and the hoisting line are in some degree actually antagonistic; that is, the hauling line, in order to draw the scoop toward the machine, must first offset by a portion of its own power, whatever outward thrust the hoisting line may be exerting on the scoop through the stick as a lever. This antagonism, though objectionable in itself, because it reduces the net live power available for actual digging, is, in practice, tolerable because it permits operating with cables only, and permits three distinct positive movements of the scoop, namely, inward, outward and upward, with but two cables. Also it will be seen that the measure of this antagonism lies in the relative proportion of two spacings, the distance from the stick pivot 7 to the pivot 14, as compared to the distance from the pivot 7 to the pivot of the bail 10.

Now, in order that the least possible amount of power may be neutralized in the digging operation by reason of the antagonism of the opposed pulls on the cables 11 and 18, the point 14 of the hoisting line attachment is located at the shortest possible distance above the fulcrum or pivot 7 of the ditcher stick; that is, the shortest possible distance which will constitute a lever arm of sufficient length to cause the stick, when in equilibrium, to be in the outward position, which is necessary for starting the excavation; and the point of attachment of the hoisting line is located in such a direction from the pivot 7, and with such angular relation to the length of the stick as to give the greatest possible effect to the power applied to the cable 18 for swinging the lower end of the stick outwardly preparatory to digging. The necessities of efficient use of power and sufficient digging range govern the location of the pivot 14 with reference to the pivot 7, both as to distance and direction, so that it can not be altered in order to secure the advantage of increased spotting or dumping range, but

the latter is secured in a practical manner by the present construction which effects a finely graduated and continuous shifting of the point at which the hoisting line stress is delivered to the upper end of the stick as the boom is raised or lowered, and the ditcher stick moved outwardly or inwardly about the pivot 7.

While I have shown and described specifically the various features of the invention and the advantages thereof, it is to be understood that these are subject to modification as long as such modification does not involve any material departure from the principles upon which the operation of the invention is based. It is, therefore, my intention to include all such modifications within the scope of the appended claims.

What is claimed is:

- 20 1. In an excavating machine, the combination of a boom pivotally mounted for up and down movement, a ditcher stick pivoted to the outer end of the boom and depending therefrom, a hoisting line, a flexible member connecting the hoisting line to the stick above the pivotal connection of the latter with the boom, the upper end of the stick having a portion engageable with said flexible member to displace the inner portion thereof as the lower end of the stick moves toward the boom, thereby increasing the distance between the ditcher stick pivot and the point at which the hoisting line stress is delivered to the upper end of the stick.
- 35 2. In an excavating machine, the combination of a boom pivotally mounted for up and down movement, a ditcher stick pivoted to the outer end of the boom, a hoisting line, and a series of interconnected links connecting the hoisting line to the upper end of the stick so as to transmit the tension of the hoisting line thereto, the upper end of the stick having means associated therewith for deflecting the links upwardly as the stick approaches the boom, and thereby continuously increasing the distance between the ditcher stick pivot and the line through which the hoisting force is delivered to the upper end of the stick.
- 50 3. In an excavating machine, the combination of a boom pivotally mounted for up and down movement, a ditcher stick pivoted to the outer end of the boom, a hoisting line, and a flexible member connecting the hoisting line with the upper end of the stick, said stick having an extended upper portion engageable with the flexible member throughout a portion of its length to increase the distance between the hoisting line of tension and the ditcher stick pivot as the ditcher stick swings toward the boom.

4. In an excavating machine, the combination of a boom pivotally mounted for up and down movement, a ditcher stick pivoted to the outer end of the boom, a hoisting line, and a flexible member connecting the hoisting line with the outer side of the stick near its upper end, said upper end having an extension upwardly and inwardly in the plane of movement of the stick about its pivot and engageable with successive points along the length of said flexible member to increase the distance between the stick pivot and the point of application of the hoisting force as the stick swings inwardly and as the connection between it and the flexible member approaches nearer to alignment with the ditcher stick pivot and the inner end of the hoisting line.

5. In an excavating machine, the combination of a boom pivotally mounted for up and down movement, a ditcher stick pivoted to the outer end of the boom and depending therefrom, a hoisting line, a flexible member connecting the hoisting line to the stick above the pivotal connection with the latter to the boom, the upper end of the stick having an upwardly bowed portion extending upwardly and inwardly in the plane of movement of said stick about its pivot, said bowed portion being engageable with the flexible member to deflect the same upwardly as the angle between the stick and the hoisting line of tension is decreased.

6. In an excavating machine, the combination of a boom pivotally mounted for up and down movement, a ditcher stick pivoted to the outer end of the boom and depending therefrom, a hoisting line, a flexible member connecting the hoisting line with the upper end of the stick above the pivotal connection of the latter with the boom, the upper end of said stick being formed with an upwardly bowed portion extending upwardly and inwardly in the plane of movement of the stick about its pivot, said extended portion being engageable with successive points along the length of said flexible member to displace the same and progressively increase the distance between the ditcher stick pivot and the point at which the hoisting line stress is delivered to the upper end of the stick as the angle between the latter and the hoisting line decreases, said extended portion at the upper end of the stick being provided with a groove in its upper face for receiving and guiding said flexible member.

In testimony, that I claim the foregoing as my own, I have hereto affixed my signature.

ROBERT REX DOWNIE.
